MACHINE FOR CEMENTING LEATHER SOLES TO SHOES

Filed May 28, 1931

Inventor

Heinrich Ebster

UNITED STATES PATENT OFFICE

HEINRICH WALTHER, OF FRANKFORT-ON-THE-MAIN-OBERRAD, GERMANY

MACHINE FOR CEMENTING LEATHER SOLES TO SHOES

Application filed May 28, 1931, Serial No. 540,698, and in Germany May 15, 1930.

The present invention refers to a machine for manufacturing of glued shoes the sole of which is integral with the leather flap covering the breast of the heel. Without the use of my invention several working steps are usually necessary for cementing of the sole and of the covering flap. At first the cement is applied to the forepart and to the instep of the sole. The part of the sole to be used as the covering flap is fastened by a peg to the heel seat of the shoe in order to keep the sole in position. Then a solvent is applied to the cement of the sole and the sole is pressed in a machine to the shoe. After the cement has set the peg is pulled out of the rear part of the sole and the heel is fastened underneath this part to the shoe. Now cement is applied to the heel part of the sole which is cemented to the breast of the heel in a second press.

According to the invention a single cementing press is used which is adapted to exert a pressure on the sole and on the breast of the heel at the same time. With the new machine several manufacturing steps requiring much time and experience are dispensed with. The presses for cementing the heel breast requiring much room in the shops are now superfluous.

In the drawing an embodiment of the new machine is shown as far as necessary for an understanding of the invention.

Fig. 1 shows the machine with a shoe placed on a pressure device of the machine before the pressure is exerted.

Fig. 1a is a view of the cam 22 with the roller 21 in a position corresponding to Fig. 1.

Fig. 2 illustrates the same parts while the shoe is being pressed.

Fig. 2a is a view of the cam 22 with the roller 21 in a position corresponding to Fig. 2.

Fig. 3 shows the parts and the shoe after the pressure has been finished.

In the shown cementing press the pressure devices are arranged starlike on a rotating shaft. But the invention may be applied to any other kind of presses for instance to presses having pressing devices coupled to

each other like a chain and moving in a horizontal direction. One device only is shown, as all devices are alike.

The carrier 4 of the pressing devices is fastened by means of the bolts 5 to the shaft 1 rotatable in the fixed journals 2 and 3. To the carrier 4 are fastened around in any suitable number the frames 6 accommodating the pressure devices. These frames carry the pressing cushions 7 having pipes 8 for supplying and exhausting the pressure medium controlled in any known manner. The pressure lever 9 is connected to the frame 6 in a manner shown in my Patent No. 1,709,293 or otherwise so as to keep the shoes in place while they are pressed and to free them after the pressing is done.

The frames 6 have lugs 10 forming journals for the heel supports. On the lug 10 is at 11 rotatably journaled the lever 12 the middle of which is bifurcated. The upper end of the lever carries the support 13 for the heel. In the bifurcation of the lever 12 a ratchet member 15 is pivoted at 14. While the machine is at rest the nose 17 of the member 15 is held by a spring 16 against the shoulder of the support 13. In the lug 10 is arranged a vertical slide 19 carrying at its upper end a roller 20 and at its lower end a roller 21. To the journal 3 of the shaft 1 is fixed a cam-disc 22 into which the roller 21 of the slide 19 engages only while the shoe is put under pressure and while it is again freed.

The shoe to be pressed with the heel already pegged on is placed with its sole on the free surface of the pressing device of the machine. The holding lever 9 is lowered on the shoe and is locked to the frame 6 in any known manner.

When the motor drive of the machine is clutched in, the shaft 1 with the pressing devices begins to rotate and the path 23 of the cam 22 pushes the roller 21 and the slide 19 upwardly for a certain amount. The upper end of the slide 19 moves by means of its roller 20, the ratchet member 15, and the spring 16 the lever 12 and the support 13 against the heel of the shoe until the support 13 snugly abuts against the heel. The slide 19 continues its upward movement, but as the

movement of the lever 12 is stopped by the support 13, the locking member 15 swings about the pivot 14 against the shoe while compressing the spring 16 until the slide 19 reaches its uppermost position. The whole 5 device is now locked in this position by the roller 20 engaging into the notch 25 of the member 15 (Fig. 2). By these means the heel is prevented from yielding rearwardly while the cushion 7 is put under pressure. 10 By introducing pressure medium into the cushion 7 the leather sole is pressed on its whole extent onto the sole of the last and the breast of the heel. The slide 19 remains automatically locked and the pressure on the 15 sole and the heel-breast remains effective even after the roller 21 leaves the cam-groove. 23. The yielding arrangement of the locking member 15 allows different heels to be worked upon. At the end of rotation of the 20 pressing wheel the shoe is to be removed from the machine. To this end the pressure is released from the sole in the known manner. Thereupon the roller 21 of the slide 19 enters the groove 24 to be pulled down into the position 25 shown in Fig. 1a. This causes the locking member 15 to be removed by the spring 16 from the lever 12 into its original position. Thereupon the whole lever 12 together with 30 the support 13, the locking member 15 and the spring 16 is moved away from the shoe to free the same (Fig. 3). The sole and the apron for the heel breast have been glued on in a single working step. A new shoe can 35 now be placed upon the empty pressing device.

What I claim is:

1. In a machine for cementing leather soles to shoes, the combination with means for 40 pressing the sole to the shoe and the heel-flap to the breast of the heel and a hold down for the shoe, of yieldingly moved means for holding the heel against the pressure exerted upon the flap.
2. In a machine for cementing leather soles to shoes, a plurality of pressing devices arranged on a movable carrier, each device consisting of means for pressing the sole to the shoe and the heel-flap to the breast of the heel, means for holding the heel against the pressure exerted on the flap, and means for automatically disengaging the means for holding the heel at a certain point of the movement of the carrier.
3. In a machine for cementing leather soles to shoes, a plurality of pressing devices arranged on a movable carrier, each device consisting of means for pressing the sole to the shoe and the heel flap to the breast of the heel, means for holding the heel against the pressure exerted upon the flap, and a fixed cam for controlling the said holding means.
4. In a machine for cementing leather soles to shoes, a plurality of pressing devices arranged on a movable carrier, each

device consisting of means for pressing the sole to the shoe and the heel flap to the breast of the heel, means for holding the heel against the pressure exerted upon the flap, and automatic means for bringing the holding means into operating position, locking them in this position and unlocking them after the travel of the carrier is finished.

5. In a machine for cementing leather soles to shoes, the combination with means for pressing the sole to the shoe and the heel flap to the breast of the heel and a hold down for the shoe, of movable means for holding the heel against the pressure exerted upon the flap and automatic means for moving the holding means into operative position.

In testimony whereof I affix my signature.
HEINRICH WALther.
